(57) **CLAIM**

The ornamental design for an x-ray shield, as shown and described.

DESCRIPTION

FIG. 1 is a front perspective view of an x-ray shield showing a first embodiment of my new design;

FIG. 2 is a front view thereof;

FIG. 3 is a top view thereof;

FIG. 4 is a bottom view thereof;

FIG. 5 is a side view thereof;

FIG. 6 is a front perspective view of an x-ray shield showing a second embodiment of my new design;

FIG. 7 is a front view thereof;

FIG. 8 is a top view thereof;

FIG. 9 is a bottom view thereof; and,

FIG. 10 is a side view thereof.

1 Claim, 8 Drawing Sheets(56)
